Primary Examiner — Cathron Brooks*Assistant Examiner* — Teddy Falloway(74) *Attorney, Agent, or Firm* — Irina Hass**CLAIM**

The ornamental design for a decorative display, as shown and described.

DESCRIPTION

FIG. 1 is a perspective view showing the new design for a decorative display;

FIG. 2 is a front view thereof;

FIG. 3 is a rear view thereof;

FIG. 4 side view thereof; and,

FIG. 5 is a cross-sectional view taken along line 5-5 of FIG. 3. The portions of the decorative display in FIGS. 1-5 shown in broken lines are included to show features that form no part of the claimed design.
